**COMBINED HAND GRIP AND THREAD BLOCK
FOR MANHOLES, SHIPLOCKS AND SWIMMING
POOLS**

Jan Zuidhof, 1914 Hamilton St., Orlando, Fla.

Filed July 8, 1963, Ser. No. 75,703

Term of patent 14 years

(Cl. D13—1)

FIG. 1 is a perspective view showing the front, top and right side of a combined hand grip and tread block for manholes, shiplocks and swimming pools;

FIG. 2 is a perspective view showing the front, top and left side of the combined hand grip and tread block;

FIG. 3 is a perspective view showing the rear, right side and bottom of the combined hand grip and tread block;

FIG. 4 is a vertical, sectional view through the combined hand grip and tread block; taken along the line 4—4 of FIG. 1;

FIG. 5 is a horizontal sectional view through the combined hand grip and tread block, taken on the line 5—5 of FIG. 2; and

FIG. 6 is a vertical sectional view looking toward the front of the combined hand grip and tread block, taken along the line 6—6 of FIG. 4.

I claim:

The ornamental design for a combined hand grip and tread block for manholes, shiplocks and swimming pools, as shown.
